LIBRARY SET CASE

Arthur Salm, Chicago, Ill., and Walter Henkels, Solingen-Merscheid, Germany, assignors to Arthur Salm Inc., Chicago, Ill., a corporation of Illinois

Filed Aug. 13, 1959, Ser. No. 57,177.

Claims priority, application Germany Feb. 14, 1959

Term of patent 14 years

(Cl. D22—5)

FIG. 1 is a perspective view of a library set case incorporating our new design;

FIG. 2 is a top plan view thereof;

FIG. 3 is a side view thereof;

FIG. 4 is an end view thereof taken from the right of FIG. 3; and

FIG. 5 is an end view thereof taken from the left of FIG. 3.

The scissors and letter opener handles are shown in each of the figures in broken lines for illustrative purposes only.

We claim:

The ornamental design for a library set case, substantially as shown and described.
